United States Patent [19]

Moriyama et al.

[11] Patent Number: Des. 307,708

[45] Date of Patent: ** May 8, 1990

[54] CONTROLLER FOR INDUSTRIAL INSTRUMENTATION

[75] Inventors: Tatsurou Moriyama; Masaharu Wakamatsu, both of Hyogo, Japan

[73] Assignee: Mitsubishi Denki Kabushiki Kaisha, Tokyo, Japan

[**] Term: 14 Years

[21] Appl. No.: 250,506

[22] Filed: Sep. 29, 1988

[30] Foreign Application Priority Data

Apr. 1, 1988 [JP] Japan 63-13421

CLAIM

The ornamental design for a controller for industrial instrumentation, showing our new design.

DESCRIPTION

FIG. 1 is a front elevational view of a controller for industrial instrumentation showing our new design; FIG. 2 is a rear elevational view thereof;

FIG. 3 is a top plan view thereof the bottom plan view being a mirror image;

FIG. 4 is a right side elevational view thereof the left side elevational view being a mirror image; and

FIG. 5 is an enlarged perspective view thereof wherein the broken lines are for illustrating an operating state.

FIG. 3

FIG. 1

FIG. 2

FIG. 4

FIG. 5
